SEPARATION OF DRY MATERIALS

Filed Jan. 4, 1929

UNITED STATES PATENT OFFICE

KENELM CHARLES APPLEYARD, OF BIRTLEY, COLIN WILLIAM HIGHAM HOLMES, OF LOW FELL, AND IVOR LLOYD BRAMWELL, OF BIRTLEY, ENGLAND, ASSIGNEES OF ONE-FOURTH TO THE BIRTLEY IRON COMPANY, LIMITED, OF BIRTLEY, ENGLAND

SEPARATION OF DRY MATERIALS

Application filed January 4, 1929, Serial No. 330,365, and in Great Britain January 24, 1928.

This invention relates to the separation of dry materials. It is particularly directed to the separation of slate or other impurities or refuse from coal, but it is not limited thereto, and includes the cleaning and grading of agricultural and mineral products and the like generally.

The invention will be described herein mainly with reference to the cleaning of coal.

The object of the invention is to provide an improved apparatus for this purpose.

In previous apparatus the deck riffles, at least as regards the principal part of the riffles, were disposed either across the table or when longitudinal of the table they were parallel to the tailing riffles.

The present invention consists in the employment of riffles inclined at an acute angle to the tailing riffle the angle not necessarily being uniform throughout the length of the tailing riffle or riffles.

The invention also consists in the employment of desk riffles decreasing in height from or towards the tailing riffle in order that the material will flow evenly toward the tailing riffle.

The invention further consists in the employment of riffles of substantially even height across the table.

The invention also consists in the improvements in and relating to the separation of dry materials hereinafter described.

Referring now to the accompanying diagrammatic drawing:

Figure 1 illustrates the plan of a deck or table according to one form of the present invention.

Figure 2 is a section on the line 2—2 of Figure 1 looking in the direction of the arrows.

Figure 3 is a section on the line 3—3 of Figure 1 looking in the direction of the arrows.

Figure 4 is a section on the line 4—4 of Figure 1 looking in the direction of the arrows.

Figure 5 is a section on the line 5—5 of Figure 1 looking in the direction of the arrows.

Figures 6 and 7 are sectional views showing different arrangements of riffles, and are to be regarded as taken on line 4—4 of Fig. 1.

In carrying the invention into effect in the form illustrated with reference to Figures 1 to 5 by way of example, the deck or table *a* is provided with banking bars *b* and *c*, riffles *d* and *e*, tailing riffles *f* and *g*, feed end *h*, and delivery end *i*, said banking bars, as customary, being of greater height than the tailing riffles.

The deck riffles *e* of the feed or preliminary section are arranged at an angle *j* to the tailing riffle of about 10°, the angle of inclination *k* of the tailing riffle *g* to the horizontal line *l* joining the front end *m* of the feed section with the end *n* of the delivery section being about 12° in the form illustrated. The tailing riffle *f* of the concentrating area or delivery section is inclined at an angle of about 160° in the form shown to the line *n*.

The deck riffles *d* of the concentrating area as shown make varying angles with the trailing riffle *f*, the inclination being from about 5° to 40°, the riffles making the smaller angles being those nearest to the delivery end *n*. The riffles *d* are shown curved, references to curved riffles are to be found in our co-pending application Serial No. 330,364, filed January 4, 1929. The riffles *e* may also be curved throughout the whole or part of their length, making suitable equal or varying angles with the tailing riffle *g*.

The connections of the riffles *d* to the riffles *e* should preferably be such as to avoid sudden changes or brakes in the movement of the coal or the like.

The above description may be taken as applying to one half of a Duplex table. With a Duplex table a banking bar *c* is not necessarily required. In what may be termed the half table or a single table such as that shown in Figure 1 where a banking bar *c* is used, this may be curved. Reference to curved banking bars and other matters which may be used in connection with the present application is to be found in our co-pending application.

The invention may be applied to tables in which separation is effected by means of vibration plus air pressure, and to those cases where no vibration is employed. It may also 5 be applied in connection with separation or stratification by air pressure, where air is employed for the purpose of loosening the bed of coal or the like, sometimes called static pressure, or where separation is effected in 10 part or substantially by the velocity of the air.

Having now described our invention what we claim as new and desire to secure by Letters Patent is:—

In a device of the class described comprising 15 an elongated table having a preliminary feed section and a concentrating section, a banking bar and a tailing riffle extending along the longitudinal edges of the table, the feed section having groups of straight riffles 20 thereon extending diagonally across the table and disposed in acute angular relation with respect to the tailing riffle, and a group of curved riffles upon the concentrating section and extending in a substantially longitudinal 25 direction of the table and disposed in acute angular relation with respect to the tailing riffle, the riffles of the concentrating section varying in angularity.

In testimony whereof we have signed our 30 names to this specification.

KENELM CHARLES APPLEYARD.
COLIN WILLIAM HIGHAM HOLMES.
IVOR LLOYD BRAMWELL.
